[57] CLAIM

The ornamental design for a casino chip holder, as shown and described.

DESCRIPTION

FIG. 1 is a perspective view of a casino chip holder, showing my new design, shown in an opened condition;

FIG. 2 is a perspective view thereof, shown in a closed position;

FIG. 3 is a top plan view thereof;

FIG. 4 is a right side elevational view thereof, the other side being identical;

FIG. 5 is a front view thereof; and,

FIG. 6 is a rear view thereof.

The broken line showing of the chip is for illustrative purposes only, and forms no part of the claimed design.
